ANNEALING FURNACE

Clarence B. Hoak, Steubenville, Ohio

Application July 29, 1937, Serial No. 156,382

2 Claims. (Cl. 72—101)

The present invention relates generally to annealing furnaces, and more particularly to a portable annealing furnace of the bell or crane movable type which includes means for supplying heat to material being annealed both through convection and through radiation.

An object of the present invention is to provide an annealing furnace which includes means for supplying heat to material being annealed, both through radiation and through convection.

Another object is to provide a portable annealing furnace which includes heat radiating walls.

Another object is to provide a portable annealing furnace which includes heat radiating walls spaced from a refractory lining to provide an extended heat conduit.

Another object is to provide an improved fabricated portable annealing furnace.

Another object is to provide an annealing furnace which has sectional heat radiating walls maintained in assembled relation by novel removable anchor tile and bolt assemblages.

Another object is to provide a portable annealing furnace including a structural frame supporting a refractory lining, spaced heat radiating walls, burners between the lining and walls, and suitable circumferentially located gas and air conduits operatively connected to the burners.

Another object is to provide an annealing furnace which includes a continuous stationary base having a plurality of stations and a movable furnace of the bell type adapted to be located over a selected station.

Another object is to provide an annealing furnace which includes means for efficiently and effectively employing substantially all of the heating medium supplied in the treatment of material being annealed.

Another object is to provide a continuous stationary base including a continuous channel or spaced continuous channels, each of which has a plurality of openings to the surface thereof, and including a plurality of stations, each of which has a frame to receive a portable annealing furnace and guide posts to position the furnace on the frame.

Other objects and advantages will be apparent from the following description, taken in conjunction with the accompanying drawings, in which:

Figure 1 is a top plan view of a portable annealing furnace constructed in accordance with the concepts of the present invention;

Fig. 2 is a side elevation of the annealing furnace shown in Fig. 1, certain portions being broken

away for clarity, and the base being shown in section;

Fig. 3 is an end elevation of the annealing furnace shown in Fig. 1, the base being shown in section;

Fig. 4 is a section on the line 4—4 of Fig. 3;

Fig. 5 is a section on the line 5—5 of Fig. 4;

Fig. 6 is a section on the line 6—6 of Fig. 2; and

Fig. 7 is an enlarged section fragment taken on the line 6—6 of Fig. 2, showing in detail burner, radiating wall, and casing construction.

Referring to the drawings more particularly by reference numerals, 10 indicates generally a portable annealing furnace constructed in accordance with the present invention, which includes a reinforced fabricated metal casing 11 having side walls 12 and 13, end walls 14 and 15, and a top 16, all of sheet steel, or the like.

The side walls 12 and 13 have inwardly directed flanges 17 and 18, respectively, welded thereto for a purpose to be described. Channel beams 21 and 22 are fixed to and along the upper edges of the sides 12 and 13, respectively (Fig. 6). The top 16 includes along the sides double bent flanges 23 and 24, the free edges of which abut the channel beams 21 and 22, respectively, and are maintained in fixed position relative thereto by angle beams 25 and 26.

The casing 11, which is generally of rectangular configuration, is maintained as a rigid unit by substantial reinforcing. Vertical I-beams 30 are disposed adjacent and fixed to the ends 14 and 15, and spaced vertical backed in pairs channel beams 31 are disposed adjacent and fixed to the sides 12 and 13 (Fig. 5). The I-beams 30 and the backed channel beams 31 are connected at their upper extremities by gusset plates 32 and 33, respectively, to I-beams 34 and 35, respectively. The I-beams 34 and 35 are connected by gusset plates 36 to form, in effect, a continuous rectangular frame (Figs. 1 and 2). The I-beams 34 are connected by longitudinally disposed I-beams 37 to the top 16 and the end walls 14 and 15.

There is connected to the I-beams 35 and the I-beams 37 a suitable hoist frame generally designated 40. The hoist frame 40 is of X-construction and includes the enlarged I-beams 41, 42, 43, and 44 which are disposed in the form of an X. The diverging ends of the I-beams 41, 42, 43, and 44 are connected by gusset plates 45 to the I-beams 35 and to transversely disposed reinforcing I-beams 46 and 47. The converging ends of the I-beams 41, 42, 43, and 44 are connected by top and bottom gusset plates 48 and 49, respectively.

tively, to which is connected by bolts 50, or the like, a hanger bracket 51 having a shaft 52 at the top thereof around which a hook is adapted to be disposed.

- 5 The I-beams 30 and the backed channel beams 31 are reinforced by two series of vertically spaced channel members 55 and 56 which extend completely around the casing 11. Small plates 57 and 58 serve to assist in maintaining the channel beams 55 and 56, respectively, in reinforcing positions. A continuous box beam 60 is connected to the I-beams 30 and the backed channel beams 31 adjacent their lower extremities and serves both to reinforce the annealing furnace construction and to conduct air for a purpose to be described.

To the lower extremities of each of the backed channel beams 31 and at right angles thereto is connected a pair of short backed channel beams 20 62 (Figs. 2 and 7). The backed channel beams 62 extend inwardly to the depth of and are fixed to the flanges 17 and 18, each pair of beams 62 being spaced by a gusset plate 63 which extends upwardly to the box beam 60 and in between the 25 spaced channel beams 31 and is fixed to both. A vertically disposed continuous plate 64, or series of small connected plates, is connected to the interior ends of each series of beams 62 and to a respective flange 17 or 18. A continuous plate 65, 30 or series of small connected plates, is connected to and beneath each series of beams 62. Angle brackets 66 are connected to the plates 64 interiorly thereof for a purpose to be set forth (Fig. 7). It is apparent that a continuous L-beam, or a 35 series of small connected L-beams, having parallel long and short vertical legs can be used instead of a continuous plate 64 and brackets 66, or series of small connected plates 65 and brackets 66. Short angle beams 67 are connected to the plates 40 65 and the beams 62. Short channel beams 68 extend between and are fixed to the flanges of the backed channel beams 62 of each series. A continuous strip plate 69 is connected to the lower side of each plate 65 at its free end.

45 A channel beam 75 is disposed beneath the lower extremities of each series of I-beams 30. An angle beam 76 is disposed between each adjacent pair of I-beams 30 and is connected to the edge of the inner flange of each channel beam 75 and to the outer surface of the respective end of the casing 11. A strip 77 is fixed to and beneath each channel beam 75 and is connected at its ends to the strips 69 which together form, in effect, a continuous rectangularly shaped strip. A horizontal disposed continuous plate 80, or series of small horizontal disposed plates 80, is fixed to the lower edge of each of the ends 14 and 15 (Fig. 4).

The casing 11 of the annealing furnace 10 which has just been described in its substantial 60 details is fabricated of construction members of suitable dimensions and materials to produce a rigid casing, welding being preferred as the connecting means. It is, of course, obvious that the particular construction members specified above 65 may be varied to secure the same or greater strength.

The casing 11 supports interiorly the fire elements of the furnace 10. At each end of the casing 11 supported upon the horizontally disposed 70 plate or plates 80 is a wall 85 of high temperature insulating tile or brick. A wall 86 of similar material is supported by each of the flanges 17 and 18, which are disposed against the interior faces of the sides 12 and 13, respectively. Interiorly of 75 and adjacent each wall 86 is a refractory wall 87

of tile, or the like, which is also supported upon the respective flange 17 or 18. The wall 87 overlaps the wall 86 by the cap portion 88.

Upon each series of brackets 66 and adjacent the respective plate 64 is a series of high temperature insulating tiles 89 which, together with the respective flanges 17 or 18, supports a series of burner blocks 90, each of which has a funnel-shaped burner aperture 91 therethrough (Fig. 7). A radiant wall 92 is supported on each series of 5 burner blocks 90 in a vertical position spaced from the wall 87 by spacer blocks 93. The radiating walls 92 comprise superposed blocks 94 of a refractory material which has a high factor of radiation, and are stacked through tongue and groove 10 connections 95, or the like. Two longitudinal radiating walls 92 are shown, but it is to be understood that end radiating walls and associated elements may be used, if desired.

The blocks 94 are maintained in position by a 20 plurality of long bolt shafts 96, which are threaded at one or both ends, and anchor tiles 97 having enlarged heads 97', one of which is disposed at each converging juncture of the blocks 94, each exterior block having only two reduced 25 corners 94', as is evident from Fig. 4, each interior block 94 having reduced corners 94'. The specific configuration of the reduced corners 94' is clearly shown in Figs. 4 and 7. Each reduced corner 94' has a right angle shelf formed therein, the 30 surface of which is substantially parallel to the sides of the block 94. The shoulders of each shelf are substantially vertical relative to the plane of their block 94, and intersect at substantially right angles. Through each anchor tile 97 a bolt shaft 35 96 extends to receive a nut 98. Each anchor tile 97 abuts its associated spacer block 93 and is drawn thereagainst. Each bolt shaft 96 extends through a spacer block 93, a wall 87, a wall 86, and the respective side 12 or 13 to protrude exteriorly of the casing 11 to receive thereon a spring clip 99 and a nut 100. Certain of the bolt shafts 96 are longer than others and extend through the space between the backed channel beams 31 as well as through the before- 40 enumerated structure (Fig. 7). This construction permits the removal of an individual tile block 94 merely by withdrawing two anchor tiles 97, for a slight clearance is provided between the reduced corners 94' and the grooves defined by the heads 45 97' and the spacer blocks 93.

An arch 103 forms the roof of the interior structure and extends between the cap portions 88 of the walls 87, being associated therewith by longitudinally extending refractory tiles 103' 55 which fit into the channel beams 21 and 22. Longitudinally extending refractory tiles 104 are also provided, though the main portion 105 of the arch 103 is of high temperature insulation tile. The refractory tiles 103' and 104 prevent heat 60 erosion at the point where the heated gases pass into the furnace interior. Between the convex side of the arch 103 and the interior of the top 16 of the casing 11 is insulation 106, which may be of any preferred material.

A blast burner 107 is disposed beneath each burner block 90 and leads into the funnel-shaped aperture 91. A branch pipe 108 connects each burner 70 107 with the box beam 60 (Figs. 6 and 7). A branch pipe 109 connects each burner 107 with a gas pipe 110, which extends around the casing 11 and which is disposed in a convenient position above the box beam 60. In each branch pipe 109 are a valve 111 and a control valve 109'; in 75

each branch pipe 108 is a control valve 108'. These valves are of any preferred construction.

In a preferred construction there are sixteen burners 107 along each longitudinal radiant wall 93. Adjacent each burner 107 is an inspection and burner lighting aperture 112 which extends through the walls 86 and 87 and the respective side 12 or 13. A removable cover 113 is disposed over the exterior terminus of each aperture 112. It is to be understood that oil and other suitable fuels may be used instead of gas, such use requiring only different burners.

A blower 115 is disposed at the top of and adjacent the end 15 of the casing 11 and is connected to the box beam 60 by a suitable pipe 116. Suitable flexible connections are provided between the gas pipe 110 and a gas line, the pipe 110 being adapted, of course, to carry gas to the burners 107. At diagonally opposed corners of the casing 11 are brackets 120 having apertures 121 therethrough. A ladder 122 is connected to the end 15 of the casing 11, and leads to a walkway 123 (Figs. 1 and 4), by means of which an individual can manually engage a powered hook under the shaft 52. Peep holes 124 having covers 124' are provided through the end walls 85 and the ends 14 and 15 for inspection purposes.

A suitable permanent foundation 125 is provided for the above described portable annealing furnace 10. Within concrete 125' are two longitudinally extending channels or conduits 126 which are lined by fire brick 127, or the like, although a greater or a lesser number of channels 126 may be used, if desired. Similarly, that portion of the foundation 125 which is adapted to lie within the interior of the annealing furnace 10 is faced with fire brick 128, or the like. Spacer blocks 129 are disposed on the fire brick face 128 to receive in a spaced relation to the fire brick facing 128 the material to be annealed. A plurality of apertures 130 having dampers 130' is provided in the brick facing 128, which lead from the floor of the foundation 125 into the channels 126 (Figs. 3 and 4). An I-beam 137 is embedded in the concrete 125' at each side thereof, the I-beams 137 (Fig. 6) being predeterminedly spaced to receive in contiguous relation the plate strips 69. Similarly disposed and embedded in the concrete 125' are I-beams 138 (Fig. 4) which receive in contiguous relation the plate strips 71. There are usually four spaced I-beams 138 for a purpose to be described. Diagonally opposed vertical posts 140 are fixed adjacent the longitudinal sides of the foundation 125 and are fixed to the I-beams 137 by braces 141 (Figs. 1 and 6).

In Figs. 5 and 6 there are shown within an assembled annealing furnace 10 upon the blocks 129 stacks 131 of sheet metal which are disposed within sealed casings 132. As shown, each casing 132 includes a base 133 and a cover 134 which are sealed by sand 135, or the like.

The foundation 125 with its associated elements may be continuous throughout its longitudinal extent substantially three times the length shown in Fig. 4.

Operation.—The movable annealing furnace 10 is adapted to be moved by a crane, or the like, between a series of permanent foundations or along a continuous permanent foundation 128. The material to be annealed is stacked in sealed casings 132 which are placed upon the blocks 129 (Fig. 6) over the foundation 125, and the an-

nealing furnace 10 is then disposed about the material, the brackets 120 being disposed around the posts 140 to properly position it. The furnace 10 is lowered into position until the strip plates 69 and 71 are in contiguous relation with the embedded I-beams 137 and 138, respectively. A connection is made between the gas supply and the pipe 110. The gas and air valves are adjusted and the burners 107 are ignited as the proper mixture of gas and air is passed through them. The gases of combustion pass upwardly between the radiant walls 92 and the walls 87 and carry the heat by convection into the interior of the annealing furnace 10. The heated gases will follow paths as indicated by the arrows A in Fig. 6. A certain percentage of the heat given off by the burners 107 will pass directly through the radiating walls 92 and will be radiated against the material being annealed. The material being subjected to the heat treatment is thus evenly and thoroughly treated by the heat through the passage of the heat to it both by convection and radiation. The material being annealed is thus treated on all sides, inasmuch as the gases of combustion follow the paths indicated by the arrows A and the heat passed off by radiation is thrown directly against the adjacent sides of the containers 132. The gases of combustion exhaust from the annealing furnace 10 through the apertures 130 into the channels 126, whence they are exteriorly vented in a suitable manner.

It is thus clear that there has been provided an annealing furnace which, by the use of convection and radiation, thoroughly and efficiently anneals material placed therein. All of the objects and advantages sought are obtained by the construction described.

It is to be understood that the foregoing description and accompanying drawings have been given by way of illustration and example and not by way of limitation, the invention being limited only by the following claims.

What is claimed is:

1. In an annealing furnace, a wall, said wall comprising a plurality of blocks having corners of right angle shelf configuration, and means to maintain said blocks in wall formation comprising anchor tiles having enlarged heads and reduced portions disposed at each four point junction of the blocks, members contiguous to the reduced portions of said anchor tiles remote from said enlarged heads and overlying portions of the contiguous blocks, and means maintaining said blocks and said members in contiguous relation, the said corners of said blocks resting between said enlarged heads and said members.

2. In an annealing furnace, a wall, said wall comprising a plurality of polygonal blocks disposed in a plurality of tiers, the blocks of the intermediate tiers being cut away at all corners, the blocks of the uppermost and lowermost tiers being cut away at the interiorly disposed corners, an anchor tile disposed at each four-point junction, each anchor tile including an enlarged portion overlying a portion of each of the adjacent blocks and a reduced portion abutted by a portion of each of said adjacent blocks, a member disposed in abutting relation with the free end of the reduced portion of each tile, said member overlying a portion of each of the adjacent blocks, and means securing the respective tiles and members in rigid relation.

CLARENCE B. HOAK.
